United States Patent Office

Des. 194,156
Patented Nov. 27, 1962

194,156

SALT SHAKER OR SIMILAR ARTICLE

Martin Schnur, West Orange, and Mel Appel, Murray Hill, N.J., assignors to Deka Plastics, Inc., Elizabeth, N.J.

Filed Apr. 19, 1962, Ser. No. 69,779

Term of patent 14 years

(Cl. D44—22)

FIG. 4

FIG. 1

FIG. 2

FIG. 5

FIG. 3

We claim:

The ornamental design for a salt shaker or similar article, as shown.
